3,166,764 MEN'S UNDERSHORTS

Sarah W. Stedman and Luther W. Self, Asheboro, N.C., assignors to Stedman Manufacturing Company, Asheboro, N.C., a corporation of North Carolina

Filed Mar. 21, 1961, Ser. No. 97,986

1 Claim. (Cl. 2—224)

This invention relates to men's wearing apparel and more particularly to a man's undergarment or brief as described in application Serial No. 25,433 and now abandoned, filed by us on April 28, 1960, entitled Men's Wearing Apparel and of which this present application is a continuation-in-part.

It is desirable in men's briefs that the brief give a trim and neat fit while at the same time offering gentle and substantial support to the wearer. Further it is desirable that the brief be so constructed as to eliminate any tug in the waistline when the wearer moves. We propose a novel undergarment which achieves the above advantages and which at the same time may be economically made from knitted or other materials which are readily available on the market.

Broadly, a brief constructed according to our invention comprises a front part, a back part, and a pouch part. The front and back parts are stitched together along vertically extending sides and have an elastic waistband sewn along their top edges to form a waist opening. The pouch part is sewn along one edge to the front part and is joined to the back part by a separate expansion gusset piece in order to form a crotch portion. Leg bindings are sewn to the lower edges of the front and back parts and to a portion of the edges of the pouch part to form two leg openings separated by the crotch portion. The bottom edge of the front part is cut along an arcuate line extending from one leg opening to the other leg opening to define a fly opening with the pouch part.

A first non-elastic or non-extensible tape is sewn to the front part and along one edge of the pouch part so that it extends in a diagonal direction from the waistband to a leg opening. A second non-elastic or non-extensible tape is partially sewn to the front part and along an edge of the pouch part so that it extends in an opposite diagonal direction to the first tape crossing with the first tape and so that it joins the elastic waistband with the other leg opening. The second tape, however, is not sewn to the front part below where the two tapes cross in order to form the fly opening.

The pouch part itself may be lined with a soft knitted material in order to give additional comfort and support or it may comprise a single layer of rubberized expandable fabric. Where the rubberized fabric construction is used, we find it advisable to stitch the rubberized fabric and gusset to a separating tape rather than directly together in order to prevent unravelling.

Referring to the drawings in which a preferred embodiment of our invention is shown,

FIG. 1 is a front view of a pair of men's briefs constructed according to our invention;

FIG. 2 is a view of the brief of FIG. 1 turned inside out and illustrating in particular the backside of the front part of the brief shown in FIG. 1;

FIG. 3 is a view of FIG. 1 taken along lines 3—3;

FIG. 4 is a sectional view of FIG. 1 taken along lines 4—4;

FIG. 5 is a sectional view of FIG. 3 taken along lines 5—5; and

FIG. 6 is a front view similar to FIG. 1 of a different embodiment of our invention.

Referring to FIG. 1 in greater detail, 1 illustrates a front part of a man's brief while 2 represents a back part which is joined to the front part by vertically extending

2

seams 3 and 4. The upper edges of parts 1 and 2 in turn are joined by an elastic waistband 5.

The lower portions of parts 1 and 2 have leg bindings 6 and 7 sewn thereon which define two leg openings. Bindings 6 and 7 may be made either of an elastic or non-elastic material.

A first non-elastic or non-extensible tape 8 is sewn onto the front part 1 and along an edge of a pouch part 12 so that it extends from the elastic waistband 5 to the binding 7. A second non-elastic or non-extensible tape 9 is sewn along a portion of its length to the front part 1 and to the pouch part 12 as shown more clearly in FIG. 2. That part of tape 9 below where it crosses with tape 8 and where it is not sewn to the front part defines 15 with the pouch part 12 and front part 1 a fly opening 10.

Part 1 is cut along an arcuate line 11, as shown in FIG. 2, so that the pouch forms an overlap at the fly opening. The pouch may be lined with a second layer of soft material 13 which may be of different texture than 20 the material comprising the front and back parts. The construction of the pouch as shown provides a substantial and gentle support for the wearer.

In addition to the novel pouch construction shown, we provide also for an expansion gusset 14, as shown in FIG. 3, to be included in the crotch portion between the leg openings of the brief. The expansion gusset 14 is made of a knitted ribbed cotton material which is stretchable laterally of the leg openings. The gusset as shown tends to eliminate any tug of the waistline of the wearer 30 when the wearer turns.

Reference is now made to FIG. 6 in which a different embodiment of our invention is shown. In this form of the invention, the pouch part 12' comprises a single layer of a rubberized elastic material which gives an additional support to the wearer. It has been found that to keep 35 the rubberized material from unravelling, it is important that the pouch not be sewn directly onto the expandable gusset 14. Rather the pouch and gusset should both be sewn onto a tape 15 of the same material as that of tapes 8 and 9.

The pouch of both forms of our invention is initially formed before the straps 8 and 9 are sewn onto it and before it is joined to the front part. As shown in FIGURE 1, the pouch part has an outwardly extending V-shaped, upper end, the edges of which are adapted to be sewn to the tapes 8 and 9. The bottom of the pouch is initially cut so that there are two diverging legs forming a V-shaped notch. These legs are then sewn together along their adjacent edges to form a seam 16 which will 50 then give the pouch a bowed-out shape. The pouch is then turned inside out so that the rough side of the seam is outside the brief.

Preferably the material comprising the front and back parts is a knitted material although other material could 55 be used.

It is to be understood that changes in the described structure may be made without departing from the spirit of the invention which scope is to be determined by reference to the following claim.

60 WE claim:

A man's undergarment comprising a front part and a back part, a pouch part of rubberized, expandable fabric having a V-shaped notch at its lower portion joined together along the edges of said notch to give a pre-formed 65 bowed shape, an elastic waistband joined to the top edges of said front and back parts to form a waist opening, two leg bindings secured to the edges of said front and back parts and lower side edges of said pouch part to form two leg openings, a first non-elastic tape joined onto 70 said front part and along an upper edge of said pouch part extending diagonally from said waistband to a leg opening, a second non-elastic tape extending diagonally

from said waistband to the other of said leg openings and crossing with said first non-elastic tape substantially in the center of said front part, said second non-elastic tape being joined along a portion of its length to said front part and along the remaining portion of its length to an upper edge of said pouch part with the portion joined to said pouch part forming a fly opening with said front part, an expansion gusset secured at one edge to the bottom edge of said back part, and a non-elastic tape connecting the other edge of said expansion gusset to the bottom of said pouch part and extending from one leg to the other leg binding.
